UNITED STATES PATENT OFFICE.

JOHN F. O'CONNOR, OF CHICAGO, ILLINOIS, ASSIGNEE TO WILLIAM H. MINER, OF CLARK, NEW YORK.

YOKES FOR RAILWAY-CAR DRAFT-RIGGING.

1,196,350.

Specification of Letters Patent. Patented Sept. 19, 1916.

Application filed November 20, 1914. Serial No. 373,034.

To all whom it may concern:

Be it known that I, JOHN F. O'CONNOR, a citizen of the United States, residing at Chicago, in the county of Cook and State 5 of Illinois, have invented a certain new and useful Improvement in Yokes for Railway-Car Draft-Riggings, of which the following is a full, clear, concise, and exact description, reference being had to the accompanying drawings, forming a part of this 10 specification.

This invention relates to improvements in yokes for railway car draft riggings.

An object of the invention is to provide 15 a yoke for draft riggings which comprises two separately formed members having means for connecting the same to prevent lateral separation thereof when the parts are in operative position.

20 The invention furthermore consists in the improvements in the parts and devices and in the novel combinations of the parts and devices, as herein shown, described or claimed.

25 In the drawing forming a part of this specification, Figure 1 is a side elevation of a yoke embodying my improvements. Fig. 2 is a top plan view of the structure illustrated in Fig. 1. Figs. 3 and 4 are enlarged 30 vertical sectional views taken on the lines

3-3 and 4-4 respectively of Fig. 1 and Fig. 5 is a horizontal detail sectional view taken on the line 5-5 of Fig. 3. Figs. 6 and 7 are views corresponding respectively 35 with Figs. 1 and 2 and illustrating another form of my improvements. Fig. 8 is a sectional view taken on the line 8-8 of Fig. 6. Fig. 9 is a horizontal detail sectional view taken on the line 9-9 of Fig. 6 and 40 Fig. 10 is a detail perspective view of the filler block employed in the structure illustrated in Figs. 6, 7, 8 and 9.

Referring first to the structure shown in Figs. 1 to 5 inclusive, the yoke is shown 45 as comprising two counterpart loop members 10-10, each of which has a pocket 11 to receive a spring or other shock absorbing device, a side plate or wall 12 at the front thereof to connect the upper and lower 50 arms of the loop, said side wall 12 having an elongated slot 13 to receive a coupler key. At the rear end, each member 10 has its upper and lower arms united by an integral 55 curved end 14 on the inner side of which

is cast an integral filler flange 15 having a vertically extending widened edge 16. Each flange 15 is provided with a centrally located, slightly longitudinally elongated slot 17 and a pair of upper and lower slightly elongated slots 18-18. Co-operating with the two members 10-10 is a filler block 19 which is substantially T-shaped 60 in cross section and comprises a vertically extending front wall 20 and rearwardly extending centrally located flange 21 which, as shown most clearly in Fig. 5, extends between the flanges 15-15. Preferably cast integral with the flange 21 is a pair of oppositely extending perforated lugs 22-22 which are adapted to be seated in the slots 70 17. The flange 21 also has cast thereon and on each side thereof a pair of outwardly extending pins 23-23 adapted to take in the slots 18-18. The front wall 20 of the filler block is provided at its edge with rearwardly extending narrow flanges 24 which fit over the outer sides of the enlarged ends 16 of the flanges 15 and thus prevent the block 19 from moving laterally with respect to the two yoke members. A headed rivet 75 25 is extended through the block 19 which retains a pair of washers 26 in place and thus prevents the parts from becoming separated.

As will be apparent, on account of the elongation of the slots 17 and 18, the yoke members 10-10 are slightly relatively longitudinally movable so that in rounding curves, radial pulls on the draw bar are accommodated by the slight relative longitudinal movement between the yoke members.

Referring now to the structure illustrated in Figs. 6 to 10 inclusive, the yoke comprises two counterpart loop members 110, 95 the upper and lower arms of which are connected by rear curved walls 114, each loop member having an integral filler flange 115 on the inner side thereof at the rear, each of which flanges 115 is substantially T-shaped in cross section. A filler block 119 is provided, which is also of substantially T-shape in cross section and has a rearwardly extending web or flange 121 located centrally thereof and side rearwardly extending flanges 124 which overlap the outer sides of the enlarged front edges of the flanges 115. The flanges 115

and 121 are all centrally perforated so that the parts may be securely held together by a headed rivet 125.

I claim:—

- 5 1. A yoke for draft riggings comprising two separate loop members, each having a filler flange on the inner side at the rear thereof, a filler block having a centrally located flange extending rearwardly and be-
10 tween the said filler flanges of the loop mem- bers, and means for securing the two loop members and said filler block together to prevent lateral separation of the parts.
- 15 2. A yoke for draft riggings comprising two members each having a forwardly ex- tended filler flange on the inner side there-
of at the rear, a filler block having a rear- wardly extended flange located between said first named flanges, said block having also
20 side flanges extending rearwardly on the outer sides of said filler flanges, and means extending through said block and the filler flanges on the yoke members for preventing lateral separation of the parts.
- 25 3. A yoke for draft riggings comprising two separate loop members, each having a filler flange on the inner side at the rear thereof, a filler block having a centrally lo-

cated flange extending rearwardly and be-
tween the said filler flanges of the loop 30 members, and means for securing the two loop members and said filler block together to prevent lateral separation of the parts, said means including a rivet extended through all of said flanges. 35

4. A yoke for draft riggings comprising two loop members each having a web on the inner side at the rear thereof, a filler block having a rearwardly extending flange located between said webs, and devices per-
40 mitting slight relative longitudinal move-
ment of the two members and preventing lateral separation thereof.

5. A yoke for draft riggings comprising two loop members each having a web on 45 the inner side at the rear thereof, a filler block having a rearwardly extending flange located between said webs, and devices per-
mitting slight relative longitudinal move-
ment of the two members and preventing 50 lateral separation thereof, said devices in-
cluding pins and slots on the several parts.

JOHN F. O'CONNOR.
